UNITED STATES PATENT OFFICE

2,002,636

VACUUM-BROOM

Ward Leathers, Haworth, N. J., assignor to The Quadrex Corporation, a corporation of Connecticut

Application September 12, 1930, Serial No. 481,407
Renewed April 24, 1934

3 Claims. (Cl. 15—16)

The object of my invention is to produce an inexpensive, light-weight vacuum-broom.

This application for U. S. Letters Patent is a continuation of, and improvement on, the vacuum-broom illustrated and described in my co-pending application #474,584, and the principles involved in air filtration and dirt disposal are more fully set forth in my co-pending application #472,703.

10 The primary object of this invention is to reduce the cost of manufacture as well as to simplify the handling of a great and useful new utility namely, an inexpensive vacuum-broom. The average use of brooms in the household is three 15 times a day. The average use of vacuum-cleaners is once a week.

10 The objects of this invention are arrived at, aside from the brush mechanism and the handle-filter described in the aforementioned co-pending 20 applications, by the unique arrangement of motor suction device, dirt-receptacle, and self cleaning mechanism. A further highly important consideration is a construction and disposition of such necessary parts, made in such manner that the broom may be made entirely of sheet stampings, where heretofore castings have been used.

15 In order to set forth my invention so that all those familiar with these arts may understand, I have provided the following specifications, to which drawings are attached, of which—

Figure 1 is a vertical, partial cross-section, of my vacuum broom, a portion of the handle being broken away.

35 Figure 2 is a detail of the ported plate.

Figure 3 is a top plan view of the fan housing.

Figure 4 is a side view of same.

Figure 5 is a perspective view of the air deflector.

40 Figure 6 is a vertical, partial cross-section of the handle top.

Figs. 7 and 8 are cross-sectional views on the lines 7—7 and 8—8 respectively of Fig. 1 looking in the direction of the arrows.

45 In Figure 1, 1 is a brush-nozzle housing, preferably of stamped sheet metal. The end only is shown, but the width may be as desired. It contains a brush 2 held in at 3 by a snap-spring 4 anchored to the housing 1 as by a rivet 5. A smooth annular housing 6, preferably of sheet metal, is attached to 1 in suitable manner, as by crimping, shown at 7. Inside of 6 there is an irregular part 8, also preferably of stamped sheet metal, which furnishes the inlet-duct 9 to the fan 10 as well as the fan housing (the shape of

this part is more fully described under Figures 3 and 4). In assembly the nozzle housing 1, with the spring-latch 4 are clamped to the parts 6 and 8, and 6 and 8 may be riveted together as desired as at 11 in order to make a unit assembly of these parts.

5 The motor-housing 12 encases the motor which drives the fan 10. This housing does not require the usual ventilation openings, since it is cooled in the blast of the blower itself. This housing 10 is preferably of stamped sheet metal, and is suitably and rigidly attached to a plate 13 as by screws 12', preferably of stamped sheet metal. The plate 13 is provided with a plurality of ports consisting of notches 13' (see Fig. 2) in its periphery. 15 These ports are preferably three in number and arranged in the upper semi circular portion. They are better illustrated in Figure 2. The blast from these three ports is upward around the motor-housing and within a smooth, annular 20 casing 14, preferably of sheet metal. Attached to the housing 12 there is an air deflector 15, of irregular shape and preferably of sheet metal. Flanges 15' on both sides, tangent to the housing 12, are rigidly attached to it by spot welding or 25 rivets 16. Another flange 17, at right angles thereto, extends radially from the motor a sufficient distance to fit tightly against the inside of the outer-casing 14. The continuation of this flange, shown at 18, also approximately tightly 30 fits the outer-housing. The purpose of this air deflector is to deflect the blast from the three ports aforementioned in such manner that the heavier particles picked up by this broom will be thrown, by centrifugal force, into the dirt-receptacle 19, which is approximately the lower half 35 of the space between the motor-housing 12 and the outer case 14. Attached to the flange 17, as by rivets, on one side, or both if desired, is a spring 20. A vane, the edge of which is shown at 21, hinged at its upper extremity, is rotatively resisted by the spring 20. This vane is mechanically and operably joined to a similar vane on the opposite side of the motor-housing by suitable means conveniently consisting of a heavy 40 wire 22. 21 and 22 are shown completely assembled and are described under Figure 5. The outside edge of the vane 21 lies approximately snugly against the outside casing 14. The edge 45 requires slight modifying in order that it may swing in its arc along the curvature of the casing 14 (see Figure 5). The inner edge lies approximately snugly against the motor-casing 12 and requires no such modification. A thumb-latch 50

55

23 is disposed on the outside of the casing 14 and rotatively attached thereto at 24. On the inside of the case 14, and rigidly related to the thumb-latch 23, is a hook or projection 25 which engages the wire loop 22 when the thumb-latch is pressed down.

10 The motor-housing 12 is provided with an electric switch 26, attached to the motor-housing, the switch-lever 27 of which projects through the outer casing through a suitable opening. A rubber cushion 28, attached to 26, makes a satisfactory air-tight joint. 29 is an electric two way connection, led upward through the hollow handle 30.

15 The hollow handle 30 is of the filter handle type, as described in my aforementioned pending applications. It consists primarily of a hollow and perforated hard fibre tube, in this case rigidly attached to the housing 14 as by rivets at 31. At 32 suitable means is provided for holding the outside filtering material.

20 In assembly, parts 1, 6 and 8 are rigidly joined, making the first assembly unit. The housing 14 and the handle tube 30 are rigidly joined, and together with the latch 23, 24 and 25 make a second assembly unit. The third assembly unit consists of the motor in its casing 12, the blower 10, the port disc 13, the deflector 15 with its spring 20, the switch 26 with its soft, rubber face 28, and the pair of vanes 21 with their connector 22. (This vane mechanism 21 and 22 is more fully described under Figure 5.)

25 Unit assembly three is set into unit assembly one. Unit assembly two is then set over unit assembly three and joined to unit assembly one in suitable manner as by screws shown at 33. Before putting these assemblies together, it is necessary to draw the wire 29 (attached to assembly two) upward through the hollow handle. When these assemblies come together the switch-lever 27 comes through the opening provided for same and the hook 25 comes to such position that it engages the loop 22. It is then evident that when the thumb-latch 23 is pressed downward it raises the vanes 21 over the exhaust ports adjacent thereto, deflecting the blast from side adjacent ports through the dirt-collecting chamber 19, making it possible to blow all the dirt from side collector outward through the hollow handle 50 when the top of said handle is opened and the motor is running. The spring 20, by means of the loop 22, returns the thumb-latch 23 to its normal position. The spring 22 is stopped from overacting by the vanes 21 coming in contact with the disc 13 and the loop 22 in contact at its center position with the motor-housing 12.

55 Figure 2 shows the port-disc 13 in plan. Attached to it is the motor-housing 12, cross-sectioned at a point near said disc. It will be noted that where the housing 12 is flanged outward for attachment to 13, said flanges may be partially cut away at the port locations.

60 Figures 3 and 4 illustrate the principles involved in properly shaping the part 8. Figure 3 is a plan view over which Figure 2 is super-imposed. The dotted circle 34 indicates the periphery of the blower unit 10. The outside or centrifugally confining wall of the part 8 is developed spirally for each of the three ports, while a top flange 35 extends the material at the top edge for support purposes only.

65 Figure 4 shows how the metal is so formed as to aid in turning the blast of centrifugal air from the fan through its 90 degree angle.

In Figure 5 I have shown the deflector vanes 21 joined by the loop 22. 22 is joined to 21 in any desired manner, but where the vanes and the wire loop are made of ferrous metal, they may be satisfactorily joined by spot welding. The vanes are provided with stub shafts 36 at their inner sides and trimmed at 21' to the necessary free radius along the cylindrical wall of the housing 14 (see Fig. 1). These shafts may also be spot-welded if desired into the vanes and then snapped into recesses or depressions suitably located on the sides of the motor-housing 12. The spring tension of the wire loop 22 holds them in place and when the casing 14 surrounds them they cannot get out of position because the clearance is insufficient.

70 Figure 6 shows the upper end of the handle wherein 30 is the hollow fibre tube provided with a metal ferrule 37 which is suitably fastened to the tube 30, provided with any means of fastening 38 over which the cap 39 may be fastened by a partial turn. At 40, the filter cover is attached to the handle 30 in any suitable manner. A suitable inlet for the feed wires 29 is provided at 41.

75 In operation, the brush 2 collects the dirt on its forward side as it is moved to and fro. The dirt is carried upward through the duct 9 by suction created by the fan 10 through the ports 13', carried around the deflector 15 and exhausted through the handle. The dirt is collected in 19, 30 partially by centrifugal force, and partially by gravity when the motor is not running and the broom is handled. To clean the broom the cap 39 is removed, the end of the broom handle is pointed out an open window, or into a sack of light 35 fabric such as cheesecloth, the motor is turned on, the thumb-latch 23 is depressed, and both the filtering handle and the dirt-receptacle 19 are almost instantly cleaned.

80 I have set forth my invention so clearly that all those familiar with these arts can understand, but I wish it understood that the principles involved can be applied in many ways and by a multitude of detail constructions without departing from the spirit thereof.

45 I claim:—

1. In a suction cleaner, the combination of a main housing having a top, sides and a bottom, a tubular handle extending from the top of said housing in communication with its interior, a filter connected with said handle arranged to filter dirt-laden air received into said handle, said handle having a closure-controlled dirt-discharge opening, a motor, a housing for said motor within and spaced at the sides and top from the main housing and having its bottom at the bottom of the main housing, a fan-chamber below the main housing adjacent the bottom thereof, a fan in said chamber driven from the aforesaid motor, a suction cleaner nozzle operatively connected with the fan-chamber, partition means in the space between the main and motor housings extending lengthwise of said housings between the sides thereof and dividing said space into compartments which may be termed upper and lower in view of the inclined position of said compartments when the cleaner is in use, said compartments communicating with each other at the top, and the upper compartment being in communication with the fan-chamber through an opening in the bottom of the main housing.

2. In a suction cleaner, the combination defined in claim 1, further characterized by there being a baffle supported above the motor housing at the entrance to the tubular-handle-filter arranged to

deflect the dirt-laden air from the aforesaid relatively uppermost compartment into the opposite relatively lower compartment thereby deflecting same from passing directly up into the tubular-handle-filter.

5. 3. In a suction cleaner, the combination defined in claim 1 further characterized by there being

means for at will connecting the fan chamber directly to the relatively lower compartment whereby the dirt can be blown from said compartment upwardly into the handle and out through the discharge opening thereof.

5. WARD LEATHERS.
